UNITED STATES PATENT OFFICE.

GASTON A. BRONDER, OF BROOKLYN, NEW YORK; LUCIA R. BRONDER ADMINISTRATRIX OF SAID GASTON A. BRONDER, DECEASED.

VAPOR EXTRACTOR.

Application filed August 13, 1921. Serial No. 491,959.

To all whom it may concern.:

Be it known that I, GASTON A. BRONDER, citizen of the United States, and resident of the borough of Brooklyn, city of New York, 5 in the county of Kings and State of New York, have invented certain new and useful Improvements in a Vapor Extractor, of which the following is a specification.

This invention relates to improvements in 10 a vapor extractor. Its object is to produce a vapor extractor by means of which powdered or granulated material may be treated to extract the volatile ingredients thereof. With this invention material can be 15 heated the particles of which are too small to be treated in the vapor extractors heretofore used. A specific use of the vapor extractor is to vaporize powdered shale for 20 producing oil upon condensation of the vapor.

The organization of the vapor extractor comprises among its novel features a retort with a vaporizing chamber and a heating chamber. Means are provided to heat all 25 the particles of the material treated in the vaporizing chamber without any loss of said particles. Means are also provided to use the product of combustion that heat and vaporize the particles to preheat them. 30 Means are provided to gradually heat the material treated and to increase the volume of heat during the treatment of the material.

The accompanying drawings exemplify 35 one form of the improved vapor extractor of which Fig. 1 represents a side elevation; Fig. 2 shows a section of Fig. 1 on the line 2, 2; Fig. 3 shows a top plan view of Fig. 1; Fig. 4 indicates a section of Fig. 3 on the line 4, 4; Fig. 5 shows a section of Fig. 4 on the line 5, 5; Fig. 6 represents a section of Fig. 4 on the line 6, 6; Fig. 7 is a section of Fig. 4 on the line 7, 7; Fig. 8 represents an enlarged fragmentary top plan view of the conveyer of the extractor; Fig. 9 shows a side view of the conveyer of the extractor; Fig. 10 represents a section of Fig. 8 on the line 10, 10 and Fig. 11 is a section of Fig. 8 on the line 11, 11.

The extractor is represented with a frame, 50 comprising the horizontal bottom angle irons 20 from which extend the vertical angle irons 21 to 28 inclusive. A lower cross angle iron connects the vertical angle irons 21 and 28. A lower cross angle iron 30 connects the vertical angle irons 22 and 27. A

lower cross angle iron 31 connects the vertical angle irons 23 and 26. A lower cross angle iron 32 connects the vertical angle irons 24 and 25. A longitudinal angle iron 35 connects the upper ends of the vertical 60 angle irons 27 and 28. At one of the outer ends of the cross angle irons 29 and 30 are respectively fastened the vertical angle irons 36 and 37. To the upper ends of the vertical irons 36 and 37 is fastened the outer 65 upper longitudinal angle iron 38. To the upper ends of the vertical angle irons 21 and 22 is fastened the upper longitudinal angle iron 39. An upper cross angle iron 40 connects the angle irons 38 and 39. An 70 upper cross angle iron 41 is fastened to the vertical angle irons 22, 27 and 37. A longitudinal angle iron 42 connects the angle irons 25 and 26. A longitudinal angle iron 43 connects the vertical angle irons 23 and 75 24. An upper cross angle iron 44 connects the vertical angle irons 24 and 25 and an upper cross angle iron 45 connects the vertical angle irons 23 and 26. An intermediate longitudinal angle iron 46 connects the vertical angle irons 25, 26, 27 and 28 and 80 an intermediate longitudinal angle iron 47 connects the vertical angle irons 21, 22, 23 and 24. A cross angle iron 50 and a cross angle iron 51 connect the vertical angle irons 85 23 and 26. A cross angle iron 52 and a cross angle iron 53 connect the vertical angle irons 22 and 27.

A vapor extractor retort designated in its 90 entirety by the letter A is supported upon and fastened to the cross angle irons 50 and 52. A vapor extractor retort like A is designated in its entirety by the letter B and is supported upon and fastened to the cross angle irons 51 and 53. 95

The retort A is box shaped and comprises the U shaped upper member 60 with the flanges 61. The member 60 is connected at its ends to the similar end heads 62 and 63. An inlet opening 64 is formed in the head 63 and 100 an outlet opening 65 is formed in the head 62. A U shaped bottom member 66 has formed therewith the flanges 67. End heads 69 and 70 are connected to the U shaped member 66. A separating plate 71 is located 105 between the flanges 61 and 67, and divides the retort into the vaporizing chamber A¹ and the heating chamber A². Packing strips 68 preferably of asbestos are located between the flanges 61 and the plate 71. Re. 110

inforcing strips 73 are placed upon the flanges 61 and reinforcing strips 74 bear up against the flanges 67. Clamping bolts 75 clamp together the flanges 61 and 67 and 5 their appurtenances. Angle irons 76 and 77 are fastened to the center plate 71 and the heads 69 and 70. Guide blocks 78 are located upon and fastened to the centre plate 71 and the angle iron 76. Guide blocks 79 are located upon and fastened to the centre plate 71 and the angle iron 77. An adjusting angle iron 80 is fastened to the head 63 and to the block 79 and an angle iron 81^a is fastened to the block 78. To the inner side faces of the 10 head 60 are secured the longitudinal guide strips 81 and guide strips 82. From the roof of the head 60 extend brackets 83 with the centre guide strips 84 on their opposite faces. A conveyer is designated in its entirety by 15 the letter C and comprises the similar members D. Each of the members D comprises the similar cross walls 85 and 86 which at their middle portions are connected by the longitudinal walls 87. End walls 88 with 20 the hub ends 89 are formed with the similar cross walls 85 and 86. The end walls 88 that are adjacent to each other are riveted together by means of the rivets 90. The walls of each of the members D form the 25 similar conveying compartments D' open at their top, and bottom sides and between the members D are formed the conveying compartments D² open at their top and bottom sides. In each of the hub ends 89 is pivoted 30 one end of a link 91 by means of the pivots 92. Filling strips 93 are riveted to the links 91. The said links 91 with the filling strips 93 and the end walls 88 constitute members 35 of chains for the conveyer C.

In the vaporizing chamber A¹ are located 40 four similar oscillating screens 95, 96, 97 and 98. Each screen comprises a practically rectangular frame with the longitudinal members 99, the outer cross members 100 and 101 and the inner cross members 102. The adjacent cross members 102 of the frames are connected by the links 105. Each of the cross members is hinged to the head 60 by means of the hinges 106 which latter are 45 fastened to the said head 60. The hinges 106 that support the cross members 100 are connected by an angle iron 108 which has formed therein the openings 109. A journal bearing 110 extends from the inner face 50 of the head 60 and a journal bearing 111 is supported on the outer face of said head 60. An oscillating shaft 112 is journaled in said journal bearings 110 and 111 and has extending therefrom the cylindrical arms 113, which latter engage the openings 109 and by means of the oscillations of the shaft 112 the screens 95, 96, 97 and 98 are swung 55 over the conveyer C.

To the inner face of one of the longitudinal walls of the heating chamber A² of the 60

retort A is fastened a supporting angle iron 117 and in the opposite longitudinal wall are formed a plurality of openings 118. A plurality of box shaped gas heaters 120 to 70 128 have each its back end supported on the angle iron 117 and the other end of each gas heater extends through one of the openings 118. Each of the heaters has openings 129 in its roof, and at the front end of each is connected an air adjuster 130 of a Bunsen burner. Gas piping 131 supplies the burners with gas. The heaters are spaced in the heating chamber A² so that the spaces between them gradually decrease from the head 70 to the head 69 which heads are respectively at the inlet and outlet ends of the 80 retort A. A vapor outlet pipe 132 extends up from the head 60 of the chamber A¹. A waste gas outlet conduit 133 extends from the U shaped member 66 of the heating chamber A². An air register 134 is slidably connected to the bottom wall of the member 85 66 of the heating chamber A².

The vapor extracting retort B as already 90 stated is the same as A, but is reversed in position to A, so that the inlet of the retort B is on the same end of the retort as the outlet of the retort A, and the outlet of the retort B is on the same end of the retort as the inlet of the retort A. A feeding and 95 preheating hopper 140 has connected thereto the angle irons 141 and 142 which latter are connected to the longitudinal angle irons 42 and 43. The waste gas outlet conduit 133 extends to one of the walls of the hopper 100 140, and registers with the conduit 145 that extends through the hopper and is open at its end opposite to the conduit 133. A feeding cross conveyer E moves over the hopper 105 140 to feed it fresh powdered shale or other material operated upon a second feeding, and preheating hopper 150 has connected thereto the angle irons 151 which latter are fastened to the longitudinal angle irons 46 and 47. A waste gas outlet conduit 152 extends from the heating chamber B² of the 110 retort B and registers with the conduit 153 which latter extends through the hopper 150. The latter is open to the atmosphere at its end opposite to the conduit 152. A feeding cross conveyer F moves over the hopper 150 to feed it with fresh powdered shale or other material operated upon. A cross waste shale conveyer G is located 115 below and adjacent to the outlet end of the retort A and a cross waste shale conveyer H is located below and adjacent to the outlet end of the retort B.

A pair of journal brackets 155 are supported on the longitudinal angle irons 46 and 47. A shaft 156 is journaled in the brackets 155 and has fastened thereto the four driving sprocket chain wheels 157. Journal brackets 160 and 160^a extend 125 respectively from the vertical angle irons 130 28

and 21 and have journaled therein the cross shaft 161. The latter has fastened thereto the four idler sprocket chain wheels 162. A pair of journal brackets 163 are fastened 5 to the vertical angle irons 24 and 25. A shaft 164 is journaled in the journal brackets 163 and has fastened thereto the four idler sprocket chain wheels 165. A pair of journal brackets 168 are fastened to 10 the vertical angle irons 24 and 25. A shaft 169 is journaled in said brackets 168 and has fastened thereto the four idler sprocket chain wheels 170. The chains of the conveyer C contact with the idler sprocket 15 chain wheels 162, 165 and 170 and are in contact with and driven by the driving sprocket chain wheels 157. The conveyer C moves through both of the retorts A and B upon the respective similar separating plates 71 and 71^b thereof and the chains of the conveyers are maintained in proper operative position in the retorts by means of the guide strips 81, 82 and 84.

A spur gear 175 is fastened to the shaft 25 156 adjacent to one end thereof. Journal brackets 176 are fastened to the angle irons 28 and 36. A shaft 177 is journaled in the brackets 176. A pinion 178 is fastened to the shaft 177 and meshes with the spur gear 175. A spur gear 179 is fastened to the shaft 177. A pair of journal brackets 180 extend from the angle irons 35 and 38 and have journaled therein the driving shaft 181. A pinion 182 is fastened to the shaft 181 35 and meshes with the spur gear 179. An eccentric 183 with the rod 184 has its body portion fastened to the shaft 181. A bell crank with the arms 185 and 186 is fastened to the shaft 112, and the arm 185 is pinned 40 to the eccentric rod 184. The shaft 112^b similar to 112, of the retort B has fastened thereto the crank 187 and a link 188 has one of its ends pinned to the arm 186 and its other end is pinned to the crank 187. A driving pulley 190 is fastened to the shaft 181.

To use the retorts fresh powdered shale or other material to be treated is fed into the feeding and preheating hopper 140 by 50 means of the cross conveyer E, and into the feeding and preheating hopper 150 by means of the cross conveyer F. The driving pulley 190 is next turned by a belt not shown, by means of which the driving 55 sprocket chain wheels 157 are turned through the interposed gearing. By this means the conveyer C is moved in the direction of the arrow I in and through the retort A and in the direction of the arrow J in and through the retort B. After both 60 the retorts are charged with the fresh powdered shale or other material, jets of gas flowing from the openings 129 of the gas heaters 120 to 128 of both retorts A and B, are lit by applying a light through the

openings of the air register 134. The shale in the vaporizing chamber A¹ of the retort A and the vaporizing chamber B¹ of the retort B is heated and the vapors generated escape through the vapor outlet pipe 132 70 and 132^b and are conducted to a condenser or condensers not shown, where the condensable portions of the vapor are liquefied, producing oil which is the primary object 75 of the invention.

The conveyer C as it moves through the vaporizing chambers A¹ and B¹ draws the powdered shale over the heated separating plates 71 and 71^b. In so doing the material in each of the compartments D¹ and D² is 80 pushed by the rear wall of each compartment, and as the skin friction of the particles in contact with the separating plates 71 and 71^b exceeds the friction of the particles with each other, they rise from the bottom portion of each compartment at its rear end and from a point somewhat distant from the front wall of each compartment as indicated in Fig. 11, baring the front portion of each compartment. Simultaneously 85 with the flowing of the particles of the shale to form the elongated ridges M, their peaks come into contact with the oscillating screens 95 to 98 in each retort, and the particles of material forming the peaks of the ridges M drop into the forward empty portions of the compartments into which they were originally dumped, and into the forward portion of the next adjacent compartment to the rear. By this means practically each of the particles of the shale in the compartments is brought into contact with the heated separating plate 71 and 71^b, constituting an automatic stirring 90 of the particles of shale. The screens 95 to 98 inclusive receive their oscillations from the arms 113 of the oscillating shafts 112 and 112^b. The latter are oscillated by means of the arm 185 which in turn is oscillated 95 by the eccentric rod 184. The latter receives its oscillations from the eccentric 183 fastened to the driving shaft 181. The shale that has been heated in the retorts A and B to produce oil, is dumped respectively 100 on the cross conveyers G and H and disposed of. While the fresh powdered shale is being heated in the vaporizing chambers A¹ and B¹ of the retorts, the product of combustion of the gas heaters 120 to 128 of each retort flow through the waste gas outlet conduits 133 and 152 through 105 the feeding and preheating hoppers 140 and 150 and thereby preheat the shale in said hoppers.

Having described my invention what I 125 desire to secure by Letters Patent and claim is:

1. In a vapor extractor the combination of a conveyer having compartments open at their top and bottom sides for a material 130

- 4 to be conveyed, a plate forming a support for the conveyer and its compartments, means to move the conveyer over said plate with the material in said compartments, the 5 movements of the conveyer forming ridges in the material that project above the walls of the compartments and means to remove the peaks of the ridges and thereby distribute the material composing the ridges into 10 the bottom portion of the conveyer.
2. In a vapor extractor the combination of a retort, a separating plate in the retort dividing it into a vaporizing chamber and a heating chamber, an outlet for the vaporizing 15 chamber, heating means in the heating chamber, a conveyer containing compartments open at their top and bottom sides moving through the vaporizing chamber upon said separating plate, an oscillating 20 element in the vaporizing chamber swinging in close proximity to the top face of the conveyer, a hopper adjacent to the retort with its outlet in the path of the conveyer and means to conduct the products of combustion of the heating means through said 25 hopper.
3. In a vapor extractor the combination of a retort, a separating plate in the retort dividing it into a vaporizing chamber and a heating chamber, a vapor outlet for the vaporizing chamber, a plurality of heating means in the heating chamber spaced one from the other from the inlet end to the outlet end thereof, the spaces 30 between the heating means decreasing from the inlet end to the outlet end of the heating chamber, a conveyer containing compartments open at their top and bottom sides moving in and through the vaporizing chamber through openings in its end walls and bearing upon the separating plate, a screen in the vaporizing chamber swinging over and in close proximity to the top face of the conveyer, a feeding and preheating 35 hopper outside of and adjacent to the retort with its outlet adapted to feed the chambers of the conveyer with the material operated upon and a conduit leading from the heating chamber and extending through 40 said hopper.
4. In a vapor extractor the combination of a retort, a separating plate in the retort dividing it into a vaporizing chamber and a heating chamber, a vapor outlet for the 45 vaporizing chamber, heating means in the heating chamber, a register for the heating chamber, a conveyer containing compartments open at their top and bottom sides moving in and through the vaporizing 50 chamber and bearing upon the separating plate, screens in the vaporizing chamber swinging over and in close proximity to the top face of the conveyer, a feeding and preheating hopper outside of and adjacent to the retort to feed material op- 55 erated upon into the chambers of the conveyer, and a conduit leading from the heating chamber through the hopper to carry away the products of combustion from the heating chamber and heat the material in 70 the preheating hopper.
5. In a vapor extractor the combination of a retort with an opening in its inlet end and an opening in its outlet end, a separating plate in the retort dividing it into a vaporizing chamber and a heating chamber, a vapor outlet for the vaporizing chamber, heating means in the heating chamber, means to permit air to enter the heating chamber, a conveyer extending through the vaporizing chamber bearing upon the separating plate and having a chain formed therewith and containing compartments open at their top and bottom sides, sprocket 75 chain wheels outside of the retort engaging the conveyer, driving means for some of the sprocket chain wheels, screens in the vaporizing chamber simultaneously swinging with the movements of the conveyer over and in close proximity to the top face of the 80 chambers of the conveyer, a feeding and preheating hopper outside of and adjacent to the inlet end of the retort with its outlet end over the path of the chambers of the conveyer, a conduit leading from the heating chamber through the hopper, a conveyer over the hopper to charge it with the material operated upon and a conveyer at the outlet end of the retort to carry away the 85 material after having been treated therein.
6. In a vapor extractor the combination of a retort, a separating plate in the retort dividing it into a vaporizing chamber and a heating chamber, means in the heating chamber to heat the separating plate, a conveyer having formed therewith chambers open at their top and bottom sides moving through the vaporizing chamber and bearing upon the said separating plate, the movements of the conveyer separating the 90 particles of material operated from said separating plate at the front portion of each chamber of the conveyer and piling up said portion to form the front wall of a ridge, the rear wall of each chamber of the conveyer piling up the material to form the 95 back portion of the ridge, and means to level off the peaks of the ridges to force the particles of material on to the bared portions of the separating plate to thereby heat 100 all the particles of the material operated upon.
7. In a vapor extractor the combination of a pair of retorts, each with a separating plate dividing each retort into a vaporizing chamber having a vapor outlet and a heating chamber, a conveyer having compartments formed therewith open at their top and bottom sides moving through each 105 vaporizing chamber and bearing on the 110
- 115
- 120
- 125
- 130

separating plate thereof, means in each heating chamber to heat the separating plate and thereby the material treated, a feeding and preheating hopper at the inlet end of 5 each retort and means to conduct the products of combustion from each heating chamber to its feeding and preheating hopper.

8. In a vapor extractor the combination 10 of a pair of retorts, each with a separating plate dividing each retort into a vaporizing chamber with a vapor outlet and a heating chamber with an air inlet, a conveyer having compartments formed therewith open at 15 their top and bottom sides moving through each vaporizing chamber and bearing on

the separating plate thereof, means in each heating chamber to gradually heat the separating plate and thereby the material treated, the volume of heat gradually increasing in each retort from its inlet to its outlet end, the said material formed into ridges by the movements of the conveyer, and means to level off the peaks of said ridges and thereby force the particles there- 20 of into the compartments.

Signed at the borough of Manhattan, city of New York in the county of New York and State of New York this 28th day of July, A. D. 1921.

GASTON A. BRONDER.
